UNITED STATES PATENT OFFICE.

ELLSWORTH E. QUAINTE, OF DENVER, COLORADO.

PERMUTATION-LOCK FOR AUTOMOBILES.

1,238,435.

Specification of Letters Patent. Patented Aug. 28, 1917.

Application filed May 15, 1915. Serial No. 28,441.

To all whom it may concern:

Be it known that I, ELLSWORTH E. QUAINTE, a citizen of the United States, residing at the city and county of Denver and State of Colorado, have invented certain new and useful Improvements in Permutation-Locks for Automobiles; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in permutation locks for automobiles, my object being to provide a device of this class which shall make it practicable for the chauffeur or other person in charge of an automobile to quickly and securely lock the same against thieves or other evilly disposed persons who might be inclined to use the machine in his absence.

My improved lock is mounted in operative relation with the steering post of the machine and is equipped with a bolt adapted to enter any one of a series of recesses with which the steering post is provided, when the bolt is in the locking position. This bolt passes through a hollow core or spindle in which a pallet is located, the said core being surrounded by rotary tumblers, which when properly adjusted, have slots properly aligned to permit the movement of the bolt from the locking to the unlocked position, by virtue of the fact that the pallet is adapted to enter the aligned slots of the tumblers. When, however, the bolt is in the locked position and these tumblers adjusted so that said slots are out of alignment, the bolt cannot be withdrawn or moved from the locking to the unlocked position, except by bringing the tumblers into proper position, and this can only be done by a person who knows the combination.

Each tumbler consists of a shell angularly arranged around the core and carrying a removable disk, said shell being provided with a series of radially disposed slots while the disk is provided with a single slot only. The disk is numbered on one of its faces with the characters 0, 1, 2, 3, 4, 5, 6, 7, 8 and 9. The combination is changed by changing the position of one or more of the disks within their respective shells. Each

tumbler works in coöperation with a spool which is splined upon the core and consequently, has no rotary movement in respect thereto. This spool carries spring-actuated balls adapted to engage radially disposed recesses formed in the disk of each tumbler. One of these recesses in the disk is cut entirely through to form a slot which registers with one of the series of slots in the tumbler shell. Each disk has recesses in its exterior or peripheral edge adapted to receive a tongue formed on the shell. The combination of the lock is changed by changing the relative position of one or more of the disks within the shell, as hereinafter more fully explained.

The bolt, the spindle and the series of tumblers constitute the lock proper, and are mounted in coöperative relation with a relatively stationary sleeve through which the steering post of the automobile passes. Normally, or when the machine is regularly in use, the bolt is withdrawn from its locking position and the steering post released, whereby it may be operated in the usual manner.

Having briefly outlined my improvement, I will proceed to describe the same in detail, reference being made to the accompanying drawing, in which is illustrated an embodiment thereof. In this drawing,

Fig. 1 is a side elevation illustrating my improved lock as applied to the steering post of an automobile.

Fig. 2 is a section taken on the line 2—2, Fig. 1, viewed in the direction of the arrow, the parts being shown on a much larger scale.

Fig. 3 is a longitudinal section taken through the lock and cutting the sleeve through which the steering post passes, the latter being shown in elevation and broken away both above and below the lock, being a section taken on the line 3—3, Fig. 4.

Fig. 4 is a section taken on the line 4—4, Fig. 3, viewed in the direction of the arrow.

Fig. 5 is a fragmentary sectional detail view illustrating the collar which supports the upper-end bearing of the lock, the same being shown in connection with the relatively stationary sleeve and the steering post passing through said sleeve.

Fig. 6 is a view similar to Fig. 3. In this view, however, parts are shown in elevation which are sectioned in Fig. 3. Also in Fig. 6 the bolt as well as the upper-end bearing

for the lock are shown in two positions, one in full lines and the other in dotted lines.

Fig. 7 is a cross section taken on the line 7—7, Fig. 3, viewed in the direction of the 5 arrow.

Fig. 8 is a section taken on the line 8—8, Fig. 6, but showing the pallet in the position corresponding with the unlocked position of the bolt or the position of the bolt 10 indicated by dotted lines in Fig. 6.

Fig. 9 is a section taken on the line 9—9, Fig. 3, viewed in the direction of the arrow.

Fig. 10 is a detail view of the shell of one of the tumblers, viewed from the inside.

Fig. 11 is a detail view of one of the tumbler disks, being also an inside view corresponding with the view of the tumbler shell in Fig. 10.

Fig. 12 is a section taken through one of 20 the spools which coöperate with the tumblers on the line 12—12, Fig. 8.

Fig. 13 is an elevation of the lock shown in its position on the sleeve of the steering post of an automobile, the said post and 25 sleeve being broken away both above and below the lock. This is a view looking in the direction of arrow 13, Fig. 6.

Fig. 14 is a cross section taken on the line 14—15, Fig. 13, the steering post and 30 its sleeve being partly broken away, looking upwardly, or in the direction of the left-hand arrow.

Fig. 15 is a view taken on the same line, but looking downwardly, or in the direction 35 of the right-hand arrow.

Fig. 16 is a detail view illustrating one of the pallet members shown in connection with the bolt.

Fig. 17 is a similar view illustrating one 40 of the pallet members shown in connection with the bolt, which is sectioned for the purpose.

Fig. 18 is a detail view of one of the collars surrounding the spindle and engaging 45 the bolt on one side. This is an inside view.

Fig. 19 is a view of the same but looking at the periphery or in the direction of arrow 19, Fig. 18.

Fig. 20 is a cross section taken through 50 the lock, being a view similar to Fig. 9, but showing the pallet in a different relative position.

Fig. 21 is a peripheral view of the centrally located ring surrounding the collars 55 which embrace the bolt on opposite sides, the said ring coöperating to maintain the bolt in the unlocked position against accidental displacement.

The same reference characters indicate 60 the same parts in all the views.

Let the numeral 5 designate the lock proper, composed of a hollow spindle 6, a pallet 7, four tumblers 8, two spools 9 and a bolt 10.

65 When the device is in use as an automobile

lock as disclosed in this specification and the accompanying drawings, the opposite extremities of the hollow spindle, which is cylindrical in shape, enter cavities 12 and 13 formed in the upper and lower bearings 70 14 and 15 which are mounted by means of brazed collars 16 and 17 on the relatively stationary sleeve 18 through which the steering post 19 of the machine passes, the said post being normally rotatable within the 75 sleeve.

As illustrated in the drawing, the steering post within the sleeve and approximately centrally arranged with reference to the lock, is equipped with a bushing 20 which 80 is provided with a series of perforations 21 which are adapted to receive the inner extremity of the bolt 10 when the latter is in the locked position (see Figs. 3, 4, 6 and 15).

The collar 17 which connects the end bearing 15 with the sleeve 18 of the steering post, is brazed thereon or made fast thereto in any suitable manner; while the collar 16 which connects the upper bearing 14 with 90 the sleeve 18 has a limited sliding movement on said sleeve when the bolt and pallet are in the unlocked position.

Located within the recess 12 of the bearing 14, is a thimble 22 which is threaded 95 into the bearing at the upper end of the cavity, which is counterbored for the purpose. The lower portion of this thimble is spaced circumferentially from the outer wall of the cavity to leave room for the 100 upper extremity of the hollow spindle 6. The portion of the thimble which extends into the portion of the cavity surrounded by the adjacent extremity of the spindle, is beveled as shown at 23, while the portion of the thimble opposite the bevel is perforated as shown at 24 to receive teeth 25 formed on extensions 26 of the spindle members 27 and 28, so that when the bolt and pallet are 105 in the locking position, the upper bearing 14 is locked against endwise movement.

Consequently, it is impossible when the bolt is in the locked position to move the bearing 14 in the direction of the axis of the steering post. When, however, the bolt is in the 110 unlocked position, the pallet is moved laterally a sufficient distance to disengage the teeth 25 from the opening 24 of the thimble, thus permitting the bearing 14 to be moved to the dotted line position, making it practicable to remove the entire locking mechanism from the steering post. The bearing 14 is normally temporarily held in position

on the sleeve 18 by means of hollow projections 29 arranged on opposite sides of the 115 portion of the collar 16 which surrounds the sleeve 18, these projections containing balls 30 which are acted on by spiral springs 31, whereby they are caused to partially enter openings 32 formed in the body of the sleeve. 130

Hence, even if the pallet is moved to disengage its teeth 25 from the thimble of the bearing 14, this bearing, together with its collar, will normally maintain its position, 5 causing the adjacent end of the spindle to remain within the cavity 12 of the bearing. A slight pull, however, upon the projections 29, will force the balls 30 into the hollows of the projections and against the springs 10 31, making it practicable to move the collar and its bearings 14 sufficiently to allow the body of the lock to be disengaged from the sleeve of the steering post. This sleeve is provided with a stop pin 33, which limits 15 the upward movement of the collar, since it is not desirable to allow this collar any more movement than is necessary to permit the easy removal of the lock. As soon as the bearing 14 and the collar 16 are moved far 20 enough to permit the disengagement of the lock proper, a centrally located collar 34 which carries a yoke 35 and which centrally engages the lock between the innermost two tumblers, is also movable in the direction of 25 the axis of the steering post and endwise with reference to the lock in order to permit sufficient endwise movement of the lock to disengage the lower extremity of the spindle from the cavity 13 of the lower bearing 30 15. When the central collar 34 is thus adjusted, the opening 36 through which the bolt passes, is thrown out of register with the zone of the perforations 21 of the bushing 20, by virtue of an opening 37 in the 35 sleeve 18, which the bolt enters, said opening being elongated to permit the movement of the collar 34 for the aforesaid purpose, since the inner extremity of the bolt, when disengaged from its perforation 21 of the 40 bushing 20, may still be within the opening 37 of the sleeve, though as illustrated in the drawing (see Fig. 14), when the bolt is in the unlocked position it is completely 45 disengaged from the opening 37. This central collar 34 is connected with the sleeve 18 by a suitable fastening device 38 which enters an opening 39 in the sleeve, which is also elongated (see Fig. 6) to permit the adjustment of the central sleeve carrying 50 the yoke 35, as heretofore explained.

The hollow spindle 6 is perforated mid-way of its length as shown at 40 to receive the shank or reduced portion 41 of the bolt 10. This opening when the parts of the 55 lock are assembled, is in register with the openings 36 and 37 of the collar 34 and the sleeve 18, respectively, and also in alignment with the zone of the bushing 20 containing the perforations 21, so that as the bolt is manipulated, it may be caused to 60 pass through the openings 36 and 37 and enter one of the openings 21 of the bushing or collar 20 carried by the steering post, as heretofore explained.

65 The shank 41 of the bolt is transversely

slotted as shown at 42 to receive the pallet 7 which is composed of the two members 27 and 28. Each of these members is provided with upper and lower projections 43 and 44 which fit closely within the hollow or cavity 70 45 of the bolt. The member 28 is secured to the bolt by means of a securing pin 46, which is passed through the upper projection 43 of the pallet member and through the bolt on opposite sides, being secured in 75 place by upsetting its extremities or in any other suitable manner. By virtue of this construction, this pallet member must move with the bolt. The projection 43 of the other pallet member 27 is provided with an 80 elongated opening 47 through which the fastening pin 46 also passes. Normally, the pallet member 27 is held inwardly as far as possible within the spindle, that is to say, so that the outer extremity of the slot 47 85 is engaged by the pin 46. This is accomplished by virtue of the fact that the upper portion of the bolt is surrounded by a sleeve 48 having an interiorly projecting shoulder 49 upon which the lower or inner extremity 90 of a spiral spring 50 acts, the upper extremity of said spring bearing against a shoulder 51 formed by the enlarged upper extremity 52 of the bolt. Extending downwardly or inwardly from the shoulder 49, 95 the sleeve is provided with pins or tongues 53 which engage the upper edges of the two pallet members and serve to force them inwardly or to their lowest limit of movement within the hollow spindle, which however, 100 has its upper portion longitudinally slotted on opposite sides of the bolt to allow the pallet to move out of the spindle when the tumblers are properly adjusted to bring all of the disk slots into alignment with the 105 slot of the spindle. This spindle slot is designated by the numeral 54.

When the tumblers are in position to prevent the movement of the bolt for unlocking purposes, if an attempt is made to actuate the bolt, it can be moved for a short distance, but not far enough to disengage it from its opening 21 in the bushing or collar of the steering post. The slight movement permitted is due to the fact that 110 the pallet member 28 is cut away or notched in four places, as shown at 55, to make room for the edges of disks 56, there being four of these disks, one for each tumbler. When the tumblers are adjusted for locking purposes as just explained, the edges of the four disks 56 will act to prevent the pallet member 27 from moving, as these edges of the disks will act upon the upper edge 57 of the member 27 to prevent any movement 115 thereof. However, the bolt is permitted a slight movement or that equal to the length of the slot 47 through which the pin 46 passes. This movement of the bolt necessarily carries the pallet member 28 with it, 120 125 130

whereby the relatively narrow portions 98 of this pallet member are caused to enter slots 58 formed in the shell members 59 of the tumblers, whereby the latter are prevented from rotation. In other words, if an evilly disposed person is attempting to unlock the machine, he will naturally pull on the bolt and as he does so, the sleeve 48 as it is moved against the spring 50, will 10 act upon the shoulder 51 of the bolt and move the latter far enough to project the narrow parts 98 of the pallet member 28 into slots 58 of the shell members of the tumblers, as just described. This will lock 15 the tumblers against rotation on the spindles and further frustrate any attempt on the part of the thief to solve the combination of the lock. At the same time, the permitted movement of the bolt is not sufficient 20 to disengage it from the steering post.

Arranged on opposite sides of the bolt when the parts are assembled, are two collars 99 which are provided with top and bottom recesses 60 and 61, whereby they are 25 adapted to receive the bolt, the upper recess of each collar having an extension 62 to receive the corresponding pin or tongue 53 of the bolt. The pallet members are further recessed as shown at 63 to receive the 30 inner edges 64 of the collars 99. Were it not for the recesses 63, the edges 64 of these collars would prevent this movement of the bolt, inasmuch as they would form stops against the movement of the pallet members.

Arranged adjacent each collar 99 and on opposite sides of the bolt and surrounding the hollow spindle, is a tumbler 8 composed of a shell member 59 and a disk member 56. Each shell member has a relatively large 40 circumferential flange 65 which is corrugated or notched as shown at 66 to facilitate manipulation. This flange extends considerably beyond the annular part 67 of the shell. This annular part extends outwardly from 45 the bolt and forms a cup adapted to receive the disk member 56 of the tumbler. The shell member has a series of radially disposed slots 58 extending outwardly from a central opening 68 and in communication with said 50 opening. The disk 56 has a single slot 69 which when the disk is inserted in the shell, registers with one of the slots 58 of the shell. When the parts are assembled, one of the 55 slots 58 is always in alignment with the slot 54 of the spindle, but unless the tumblers are so adjusted that the disk slots 69 are in alignment with the slot 54 of the spindle, the bolt cannot be moved sufficiently for unlocking purposes. There are ten slots 58 in each 60 shell member of each tumbler. Each disk member 56 is provided with nine recesses 70 which are coincidently positioned with relation to a corresponding number of the slots 58 of the shell member; while the slot 69 of 65 the disk is in register with the other slot 58

of the shell member. Each disk 56 is provided with characters upon its recessed face, these characters in the specific construction shown in the drawing, consisting of 0 and the numerals 1 to 9, inclusive. The setting 70 of the combination depends upon the position of each disk 56 within its shell 59. This shell is provided with an interiorly projecting tongue 71 adapted to enter any one of a series of peripheral recesses 72 formed in the 75 disk of the tumbler. These recesses 72 are arranged in radial alinement respectively, with the ten characters on the face of the disk.

Coöperating with each tumbler is the spool 80 9 which is provided with an opening 74 to allow it to be applied to the spindle. This spool is also provided with a tongue 94 adapted to enter a groove 75 of counterpart shape formed in the spindle, whereby the 85 spool when applied to the spindle is splined thereon. This spool is also slotted both as to its body portion and its flanges, as shown at 95, to coincide or register with the slot 54 of the spindle when the parts are assembled. The periphery of each flange 76 of each spool is provided with an exterior projection 77 forming a stop to limit the travel of each tumbler in both directions, by reason of the fact that the said stop lies in the path 95 of the tongue 71 carried by the annular part 67 of each shell member of any tumbler; and the characters on the face of each disk of the tumbler are so arranged that if the recess 72 which is opposite the zero character, is 100 caused to engage the tongue 71 of the shell member when the disk is applied to the latter, if the said tumbler is turned toward the right, for instance, until the tongue 71 which extends the entire length of the annular part 105 67 of the shell member is caused to engage the stop 77 of the spool, the slot 69 of the disk will be in alinement with the slot 54 of the spindle, and consequently, in alinement with the slot 95 of the spool, and consequently in position to allow the bolt to be moved to the unlocked position, since the 110 pallet members may be moved outwardly with the bolt into the slot 69 of the disk, as well as the slot 95 of the spool. Again, if 115 in assembling the disk and shell of the tumbler, the recess 72 of the disk opposite the numeral 9 be applied to the tongue 71 of the shell, the operator in solving the combination will first turn the tumbler toward 120 the right, for instance, until the tongue 71 engages the stop 77 of the spool. He will then turn the tumbler toward the left nine spaces or steps corresponding with the distance between the recesses 70 of the disks 125 and the slots 58 of the shell. When each one of these steps is completed, the operator is notified thereof by the reason of a click or low sound due to the engagement of a ball 78 carried by the spool and acted on by 130

a spring 79 with a recess 70 of the disk. When nine of these clicks have occurred, the operator will know that the slot 69 is in the proper position for unlocking purposes or 5 to permit the pallet to enter this slot of the disk, and this is all that is necessary in order to solve the combination of the lock. In case the disk 56 is so applied to its corresponding shell that the recess 72 opposite the numeral 10 4, for instance, is caused to engage the tongue 71 of the shell, the operator will first turn the tumbler to the right as far as possible and then to the left until four clicks have been counted, in which event, the slot 69 15 will be brought into position for unlocking purposes.

Each spool 73 is arranged to coöperate with two tumblers of the lock, the stops 77 of each flange engaging the tongue 71 of 20 the adjacent tumbler. Consequently, there are two click balls 78, both of which are acted on by the same spiral spring 79 which is located between the balls and incased by a tube 80 which is located between the two 25 flanges of the spool. Each of these flanges is recessed as shown at 81 to allow the click ball to protrude sufficiently for the purpose, but preventing its escape.

As illustrated in the drawing, the lock is 30 equipped with or includes four tumblers, all of which are identical in construction with the description just given. These tumblers are arranged in assembling the lock, two on each side of the bolt. The first two 35 tumblers are placed adjacent the two collars 99 and with their peripheral flanges 65 next to the said collars, their annular or cup-shaped members extending outwardly therefrom. The next two tumblers are re- 40 versely arranged so that their annular or cup-shaped members 67 engage or abut the outer edges of the corresponding parts of the adjacent tumblers.

When so arranged, the characterized faces 45 of the two disks 56 and the two tumblers are caused to face each other and the solution of the combination of the lock depends upon the proper adjustment of the tumblers with relation to the positions of the 50 disks 56 within their corresponding shells 59. If it be assumed that the disk of one tumbler is so applied to its shell that its recess 72 opposite the numeral 1, engages the tongue 71 of its shell; and the disk of another 55 is so placed that its recess 72 opposite the numeral 2 engages the tongue 71 of its shell; and the disk of another tumbler so arranged that its recess 72 opposite the numeral 3 receives the tongue 71 of its shell 60 member; while the recess 72 opposite the numeral 4 of another disk be caused to engage the tongue 71 of its shell, all that will be necessary in solving the combination will be to first turn all of the tumblers toward 65 the right, for instance, as far as they will go, after which, one tumbler will be moved toward the left, one space or until one click is heard, after which another tumbler will be moved toward the left two spaces or until two clicks are heard, while the remaining 70 tumblers will be respectively moved toward the left three or four spaces, or until three or four clicks are heard. This will bring the slot 69 of the disks of all the tumblers into alinement with the slot 54 of the spin- 75 dle and with the slots 75 of the two spools, in which event, the bolt may be moved to the unlocked position. Thus the pallet members will both be allowed to enter the slots 69 of all the disks. At the same time, 80 the hooks 25 of the pallet members will be disengaged from the opening 24 of the thimble 22, thus making it practicable to slide the bearing member 14 endwise of the lock and longitudinally of the steering post 85 by the movement of the collar 16 on the sleeve 18 far enough to remove the lock from its position in coöperation with the steering post, as heretofore described. The bearing 14, however, is held securely in 90 place when the bolt is moved to the unlocked position by means of the spring-actuated balls 30 of the collar 16 which engage the openings 32 of the sleeve as heretofore described; and the movement of the 95 bearing 14 will never take place except when it is necessary or desirable to remove the body of the lock for any purpose. When the bolt is moved to its unlocked position, its spring 50 will be placed under tension, 100 and if the bolt were released immediately after the outward movement without changing its position, the spring would immediately return it to the locking position. But if it is desired, as it will be in order 105 to operate the machine to maintain the bolt in the unlocked position, the sleeve 48 is given a quarter rotation, whereby the inner extremities of the tongues 53 are caused to enter recesses 82 formed in the 110 abutting edges of the collars 99, portions 83 of these recesses being formed in each collar. These recesses 82 are comparatively shallow since they only have a depth equal to the thickness of the peripheral portions of the collars 99 and in the absence of any provision to prevent such an occurrence, it would be easy for the sleeve 48 to be displaced or given a partial rotary 115 movement sufficient to cause its tongues to move into alinement with the recesses 62 of the collars, thus allowing the bolt to move into locking position and lock the steering post against movement. This of course, would be a serious condition and would un- 120 doubtedly result in accident. Provision is therefore made for preventing the accidental rotary movement of the sleeve 48 when the bolt is in the unlocked position, 125 this provision consisting of a band 84 (see 130

Fig. 21) which is applied to the collars 99 exteriorly and provided with openings 85 and 86. The opening 86 is of the same width throughout its length and closely engages the inner part of the bolt on opposite sides. The opening 85 is composed of two parts 87 and 88. The part 87 is of the same width as the entire opening 86 and closely engages the reduced part of shank 41 of the bolt below the sleeve 48. This brings the adjacent portions 89 of the band on opposite sides of the part 87 of the slot directly beneath the shoulders 90 formed by the sleeve 48 of the bolt. In this event, the edges of the ring or band adjacent the part 87 of the opening will be arranged on opposite sides of the tongues 53 of the bolt so that it will be impossible to turn the sleeve into position to allow its tongues 53 to enter the recesses 82 of the collars 99, since these recesses are closed or covered by the parts 89 of the band or ring 84. When, however, it is desired to return the bolt to the locking position, the band is moved in a direction to cause the part 88 of the opening 85 which is as large in diameter as the sleeve 48 of the bolt, to assume a position surrounding the bolt. When the band or ring is in this position, the sleeve 48 may be turned on the bolt to bring its tongues 53 into alinement with the recesses 82 of the collars 99, in which event, the bolt may assume the locking position, as will be readily understood.

From this it will be plain that the sleeve 48 is freely rotatable on the body or shank 41 of the bolt. This shank member, however, has no rotary movement, since it is connected to the pallet members by the pin 46, as heretofore explained, and as these members are disposed longitudinally of the spindle and within the same, the shank of the bolt is of course, locked against any rotary action.

When the device is in use, as soon as the chauffeur or other person in charge, stops the machine, if he desires to lock it, he will adjust the band 84 to bring the enlarged portion 88 of its opening 85 into position surrounding the bolt. The sleeve 48 will then be given a quarter rotation as just explained, whereby the tongues 53 will be brought into position to enter the recesses 82, in which event, the bolt may move inwardly into engagement with one of the openings 21 of the perforated zone of the bushing 20 of the steering post. It will be understood that if an opening 21 is not in alinement with the bolt, only slight manipulation of the post will be necessary in order to bring one of these openings into such position. As soon as this is done, one or more of the tumblers are moved in the one direction or the other, in order to throw the slots 69 of the tumbler disks out of register or alinement with the

pallet and the slots 54 and 95 of the spindle 35 and the spools. Then no one can move the bolt to the unlocking position until he has adjusted the tumblers to bring all the disk slots 69 into alinement or register with each other and also into alinement or register 70 with the slots 54 of the spindle and the corresponding slots 95 of the spools, and this can only be accomplished by the person knowing the combination. This can be easily done by such person, however, since 75 when he returns and desires to unlock the machine, he will simply first move all the tumblers toward the right as far as they will go or until the tongues 71 of the shell members 59 engage the stops 77 of the spools. 80 Then, if the disks, for instance, from the bottom to the top of the lock are so set that their numerals 2, 4, 6 and 8 respectively, of the tumbler disks 56 are opposite the recesses 72 which are in engagement with the 85 tongues 71 of the tumbler members 59, the lowermost tumbler will be moved two clicks toward the left, the next higher tumbler four clicks toward the left; the tumbler next above six clicks toward the left; and the 90 uppermost tumbler eight clicks toward the left, in which event, the slots 69 of the disks of all the tumblers will be brought into alinement with each other and into register with the slot 54 of the spindle and the slots 95 of 95 the spools, allowing the pallet members to move laterally as the bolt is pulled outwardly, the movement permitted being sufficient to disengage the inner extremity of the bolt from its opening or perforation 21 of the 100 bushing 20 of the steering post. The sleeve 48 of the bolt will then be given a quarter rotation to bring its tongues 53 into position to enter the recesses 82 of the collars 99, after which the band or ring 84 will be shifted to 105 move its relatively large portion 88 away from the bolt and bring the, relatively narrow part 87 into the bolt position, thus making it impracticable to turn the sleeve 48 of the bolt sufficiently to permit the return of 110 the bolt to the locking position, except by design.

Having thus described my invention, what I claim is:—

1. A lock of the class described comprising a casing, a hollow spindle, a laterally movable pallet in said spindle which is slotted to permit the pallet to protrude, the spindle having a centrally located opening formed therethrough at right angles to its 115 axis, a bolt passing through said opening and to which said pallet is secured, and tumblers rotatably mounted on the spindle for controlling the movement of the pallet through the slot in the spindle. 120

2. A lock of the class described comprising a casing, a hollow spindle, a laterally movable pallet in said spindle which is slot- 125

ted to permit the pallet to protrude, the spindle having a centrally located opening formed therethrough at right angles to its axis, a bolt passing through said opening and to which said pallet is secured, and tumblers rotatably mounted on the spindle for controlling the movement of the pallet through the slot in the spindle, each tumbler being composed of a shell member and a disk member adjustable therein.

3. A lock of the class described comprising a casing, a hollow spindle, a laterally movable pallet in said spindle which is slotted to permit the pallet to protrude, the spindle having a centrally located opening formed therethrough at right angles to its axis, a bolt passing through said opening and to which said pallet is secured, and tumblers rotatably mounted on the spindle for controlling the movement of the pallet through the slot in the spindle, each tumbler being composed of a shell member and a disk member adjustable therein, the shell member having a series of radially disposed slots and the disk member having a single slot adapted to register with any slot of the shell member.

4. A lock of the class described comprising a casing, a hollow spindle, a laterally movable pallet in said spindle, the latter being slotted to permit the pallet to protrude, the spindle having a centrally located opening formed therethrough at right angles to its axis, a bolt passing through said opening and to which the said pallet is secured, and tumblers rotatably mounted on the spindle for controlling the movement of the pallet through the slot of the spindle, the pallet being composed of two members, one of which has a limited movement with the bolt independently of the other.

5. A lock of the class described comprising a casing, a hollow spindle, a laterally movable pallet in said spindle, which is slotted to permit the pallet to protrude, the spindle having a centrally located opening formed therethrough at right angles to its axis, a bolt passing through said opening and to which said pallet is secured, and tumblers rotatably mounted on the spindle for controlling the movement of the pallet, each tumbler being composed of a shell member and a disk member adjustable therein, the shell member having a series of radially disposed slots and the disk member having a single slot adapted to register with any slot of the shell member, the disk member having a series of characters respectively corresponding with the slots in the shell member, the latter being equipped with a stop, the disk being adjustable in the shell member to bring the slot of the disk into any desired position with reference to the stop of the shell member.

6. A lock of the class described comprising a casing, a hollow spindle, a laterally movable pallet in said spindle, which is slotted to permit the pallet to protrude, the spindle having a centrally located opening formed therethrough at right angles to its axis, a bolt passing through said opening and to which said pallet is secured, and tumblers rotatably mounted on the spindle for controlling the movement of the pallet, each tumbler being composed of a shell member and a disk member adjustable therein, the shell member having a series of radially disposed slots and the disk member having a single slot adapted to register with any slot of the shell member, the disk member having a series of characters respectively corresponding with the slots in the shell member, the latter being equipped with a stop, the disk being adjustable in the shell member to bring the slot of the disk into any desired position with reference to the stop of the shell member, the spindle having tumbler-spacing members projecting into the shells of the adjacent tumblers, the said spacing members being equipped with stops co-operating with the shell stops to limit the rotation of the tumblers in either direction.

7. In a lock of the class described, the combination of a hollow spindle having a transversely arranged centrally located opening and a longitudinally disposed slot intersecting said opening, a bolt passing through the opening in the spindle and movable longitudinally therein, a pallet connected with the bolt and extending longitudinally of the spindle, one edge of the pallet entering the slot of the spindle, the bolt being composed of two spring-spaced members, one of which is rotatable on the other, and provided with means for supporting the bolt in the unlocked position.

8. In a lock of the class described, the combination of a hollow spindle having a transversely arranged centrally located opening and a longitudinally disposed slot intersecting said opening, a bolt passing through the opening and movable longitudinally therein, a pallet connected with the bolt and extending longitudinally of the spindle, one edge of the pallet entering the slot of the spindle, the bolt being composed of a body member and an extensible spring-actuated sleeve rotatable on the bolt and provided with means for retaining the bolt in the unlocked position.

9. In a lock of the class described, the combination of a hollow spindle having a transversely arranged centrally located opening and a longitudinally disposed slot intersecting said opening, a bolt passing through the opening and movable longitudinally therein, a pallet connected with the bolt and extend-

- ing longitudinally of the spindle, one edge of the pallet entering the slot of the spindle, the bolt being composed of a body member and an extensible spring-actuated sleeve 5 rotatable on the bolt and provided with means for retaining the bolt in the unlocked position, said means comprising tongues extending downwardly from the sleeve on opposite sides of the bolt.
- 10 10. In a lock of the class described, the combination of a hollow spindle having a transversely arranged centrally located opening and a longitudinally disposed slot intersecting said opening, a bolt passing through 15 the opening and movable longitudinally therein, a pallet connected with the bolt and extending longitudinally of the spindle, one edge of the pallet entering the slot of the spindle, the bolt being composed of a body 20 member and an extensible spring-actuated sleeve rotatable on the bolt and provided with means for retaining the bolt in the unlocked position, said means comprising tongues extending downwardly from the 25 sleeve on opposite sides of the bolt, the spindle being equipped with relatively stationary collar members surrounding the same on opposite sides of the bolt and coöperating with the bolt to space the adjacent tumblers, 30 the said collars having recesses adapted to receive the tongues of the bolt sleeve, the said recesses being arranged in a plane passed through the axis of the spindle.
11. In a lock of the class described, the 35 combination of a hollow spindle having a transversely arranged centrally located opening and a longitudinally disposed slot intersecting said opening, a bolt passing through 40 the opening and movable longitudinally therein, a pallet connected with the bolt and extending longitudinally of the spindle, one edge of the pallet entering the slot of the spindle, the bolt being composed of a body member and an extensible spring-actuated 45 sleeve rotatable on the bolt and provided with means for retaining the bolt in the unlocked position, said means comprising tongues extending downwardly from the 50 sleeve on opposite sides of the bolt, the spindle being equipped with relatively stationary collar members surrounding the same on opposite sides of the bolt and coöperating with the bolt to space the adjacent tumblers, the said collars having recesses adapted to 55 receive the tongues of the bolt sleeve, the said recesses being arranged in a plane passed through the axis of the spindle, the pallet being recessed on opposite sides of the bolt to make room for vertically disposed 60 flanges with which the collars are equipped and which fit closely around the spindles, the collars being further provided with recesses arranged at right angles to the first 65 named recesses, the second named recesses 70 being adapted to receive the extremities of the tongues only, whereby the collars, when the sleeve of the bolt is properly adjusted, prevent the movement of the bolt to the locking 75 position.
12. In a lock of the class described, the 80 combination of a hollow spindle having a transversely arranged centrally located opening and a longitudinally disposed slot intersecting said opening, a bolt passing through 85 the opening and movable longitudinally therein, a pallet connected with the bolt and extending longitudinally of the spindle, one edge of the pallet entering the slot of the spindle, the bolt being composed of a body member and an extensible spring-actuated 90 sleeve rotatable on the bolt and provided with means for retaining the bolt in the unlocked position, said means comprising tongues extending downwardly from the 95 sleeve on opposite sides of the bolt, the spindle being equipped with relatively stationary collar members surrounding the same on opposite sides of the bolt and coöperating with the bolt to space the adjacent tumblers, the said collars having recesses adapted to 100 receive the tongues of the bolt sleeve, the said recesses being arranged in a plane passed through the axis of the spindle, the pallet being recessed on opposite sides of the bolt to make room for vertically disposed 105 flanges with which the collars are equipped and which fit closely around the spindles, the collars being further provided with recesses arranged at right angles to the first 110 named recesses, the second named recesses 115 being adapted to receive the extremities of the tongues only, whereby the collars, when the sleeve of the bolt is properly adjusted, prevent the movement of the bolt to the locking 120 position, and a ring exteriorly applied to the collars and slotted to permit partial rotary movement to cover the first named recesses when the bolt is in the unlocked position, a part of one of the slots being enlarged so that when the ring is properly adjusted, the bolt may move to the locking position.
13. The combination of a steering post having a portion recessed to receive a locking bolt, but a relatively stationary sleeve 125 through which said steering post passes, a lock including a bolt coöperating with the steering post for locking purposes, a permutation element, an operative connection between such element and bolt for regulating the movement of the latter in its relation with the steering post, and end bearings for the permutation element, the said bearings being connected with the said sleeve, one of said bearings being normally movable longitudinally of the sleeve, and an operative connection between said movable bearing and the permutation element, to

adapted to receive the extremities of the 65 tongues only, whereby the collars, when the sleeve of the bolt is properly adjusted, prevent the movement of the bolt to the locking position.

12. In a lock of the class described, the 70 combination of a hollow spindle having a transversely arranged centrally located opening and a longitudinally disposed slot intersecting said opening, a bolt passing through 75 the opening and movable longitudinally therein, a pallet connected with the bolt and extending longitudinally of the spindle, one edge of the pallet entering the slot of the spindle, the bolt being composed of a body member and an extensible spring-actuated 80 sleeve rotatable on the bolt and provided with means for retaining the bolt in the unlocked position, said means comprising tongues extending downwardly from the 85 sleeve on opposite sides of the bolt, the spindle being equipped with relatively stationary collar members surrounding the same on opposite sides of the bolt and coöperating with the bolt to space the adjacent tumblers, the said collars having recesses adapted to 90 receive the tongues of the bolt sleeve, the said recesses being arranged in a plane passed through the axis of the spindle, the pallet being recessed on opposite sides of the bolt to make room for vertically disposed 95 flanges with which the collars are equipped and which fit closely around the spindles, the collars being further provided with recesses arranged at right angles to the first 100 named recesses, the second named recesses 105 being adapted to receive the extremities of the tongues only, whereby the collars, when the sleeve of the bolt is properly adjusted, prevent the movement of the bolt to the locking 110 position, and a ring exteriorly applied to the collars and slotted to permit partial rotary movement to cover the first named recesses when the bolt is in the unlocked position, a part of one of the slots being enlarged so that when the ring is properly adjusted, the bolt may move to the locking position.

13. The combination of a steering post having a portion recessed to receive a locking bolt, but a relatively stationary sleeve 115 through which said steering post passes, a lock including a bolt coöperating with the steering post for locking purposes, a permutation element, an operative connection between such element and bolt for regulating the movement of the latter in its relation with the steering post, and end bearings for the permutation element, the said bearings being connected with the said sleeve, one of said bearings being normally movable longitudinally of the sleeve, and an operative connection between said movable bearing and the permutation element, to

lock the said bearing against movement when the bolt is in the locking position.

14. A lock of the class described including a hollow spindle longitudinally slotted 5 on one side and provided with a centrally located opening extending at right angles to its axis, a bolt passing through said opening, a pallet secured to the bolt, located within the spindle, extending lengthwise 10 thereof and adapted to enter the slot of the spindle, tumblers rotatably mounted on the spindle on opposite sides of the bolt and equipped with slots, the tumblers being adjustable to bring their slots into alinement 15 with the slot of the spindle, end bearings for the spindle, one bearing being equipped with a thimble having an opening to receive a hook-shaped projection at one extremity of the pallet, when the bolt is in the 20 locking position, the pallet and the bolt being movable to disengage the pallet from the thimble of the bearing, thus permitting the separation of the latter from the spindle.
15. A lock of the class described comprising a hollow spindle, end bearings for the spindle, a pallet located in the spindle and extending lengthwise thereof, the spindle being slotted to receive the pallet, the spindle having a centrally located 25 transverse opening, a bolt movable in said opening and to which the pallet is secured, bearing collars surrounding the spindle on opposite sides of the bolt, tumblers rotatably mounted on the spindle between the said collars and the end bearings, said tumblers being rotatable to control the movement of the bolt by virtue of their relation to the pallet, an interlocking connection between 30 one end of the pallet and one of the end bearings to lock the said bearing against

disengagement when the bolt and pallet are in the locking position, the bearings being released when the said parts are in the unlocked position.

16. A lock of the class described comprising a spindle having a centrally located transverse opening, a bolt passing through said opening, a pallet located in the spindle and secured to said bolt, the spindle having a longitudinal slot on one side adapted to 45 receive the pallet, tumblers rotatably mounted on the spindle on opposite sides of the bolt, each tumbler being composed of a shell member and a disk member, each shell member having a tongue and each disk 50 member having peripheral recesses adapted to engage said tongue and characters for the respective recesses, coincidently arranged, the shell member having slots radiating from the spindle opening, the disk member 55 having a single slot adapted to register with any slot of the shell member, the disk member also having recesses coincidently positioned respectively with the slots of the shell member, and tumbler-spacing devices 60 equipped with spring-actuated balls adapted to enter said recesses of the disk member as the tumblers are rotated, the said spacing devices having stops coöoperating with the 65 tongues of the shell members of the tumblers to limit the rotary movement of the latter in both directions to facilitate the 70 solving of the combination of the lock.

In testimony whereof I affix my signature in presence of two witnesses.

ELLSWORTH E. QUAINTANCE.
